United States Patent Office.

GEORGE F. STONE, OF BALTIMORE, MARYLAND.

Design No. 3,712, dated October 12, 1869.

DESIGN FOR A RETURN-BEND.

The Schedule referred to in these Letters Patent and making part of the same.

To all whom it may concern:

Be it known that I, GEORGE F. STONE, of Baltimore, State of Maryland, have invented or produced a new and original Design for a Return-Bend; and I do hereby declare that the following is a full and exact description of the same.

The nature of my design is fully represented in the accompanying photographic illustration, to which reference is made.

I claim, as my invention, the design for a return-bend, as shown.

Witnesses: GEORGE F. STONE.
